UNITED STATES PATENT OFFICE

2,108,453

MAIL CARRIER

Guy Spencer, Heyworth, Ill.

Application February 6, 1937, Serial No. 124,491

1 Claim. (Cl. 104—177)

This invention relates to new and useful improvements in conveyors and more particularly to means for conveying mail from the roadway where it is left by the mailman, to the house, which may be set back some distance from the roadway, this being especially true in rural districts.

The principal object of the invention is to provide a mail conveyor of the character stated which can be easily controlled for transporting mail from the point of deposit by the mailman to the house without any inconvenience and in a rapid and fool-proof manner.

Still another important object of the invention is to provide a mail conveyor of the character stated which is substantially automatic in operation.

These and various other important objects and advantages of the invention will become apparent to the reader of the following specification.

In the drawings:—

Figure 1 represents a side elevational view of the apparatus.

Figure 2 is a vertical sectional view taken substantially on the line 2—2 of Figure 1 without the cable.

Figure 3 is a section on the line 3—3 of Figure 1.

Figure 4 is a fragmentary perspective view of 30 the trackway.

Figure 5 is a fragmentary perspective of one end of the trackway.

Figure 6 is a top plan view of the pulley and mount at the roadway end of the conveyor.

Figure 7 is a side elevational view of the cable showing one of the enlargements thereon.

Figure 8 is a section on the line 8—8 of Figure 7.

Figure 9 is an enlarged side elevational view 40 of the mail receptacle.

Figure 10 is a sectional view on the line 10—10 of Figure 9.

Figure 11 is an enlarged edge elevational view 45 of one of the pulleys.

Figure 12 is a top plan view of the drive means and control therefor.

Figure 13 is a side elevational view of the structure shown in Figure 12 with a portion broken away.

Figure 14 is a perspective of the cable operated arm.

Figure 15 is a sectional view on the line 15—15 of Figure 12.

Referring to the drawings wherein like numer-

als designate like parts, it can be seen that the conveyor is intended to be placed between a roadway which may be indicated at 5 in Figure 1, and a house or other building 6 remotely situated with respect to the roadway 5.

The construction of the conveyor involves a plurality of suitably spaced posts 7 and the roadway post 8. At the building 6 a suitable support or bracket 9 has the drive means generally referred to by numeral 10 mounted thereon 10 and this includes a pulley 11 on the driven shaft 12. As is shown in Figures 1 and 6, the post 8 has the elongated plate 13 secured to the top thereof and into this plate 13 can be driven the threaded studs or screws 14, these studs or screws passing through the slot 15 of the shank 16 of the yoke 17 in which the pulley 18 is mounted. Obviously, by loosening and tightening these studs or screws 14 the shank 16 can be adjusted on the plate 13 for regulating the 20 tautness of the cable 19 which is trained over the pulleys 11—18.

It will be observed in Figure 11 that each of the pulleys is provided with an anti-slipping cover 20, preferably of rubber, so that the ovate-shaped enlargements 21—22 on the cable 19 can easily pass thereover. These enlargements 21—22 are at substantially diametrically opposite points on the cable.

Numeral 23 generally refers to the mail receptacle which is an elongated rectangular-shaped box 24 open at each end and provided with a hinged closure 25 at each end adapted to be held in closed position by suitable spring latch means 26. Obviously, the mailman uses one of 30 these closures in gaining access to the box 24, while the person receiving the mail uses the other closure in gaining access to the box for retrieving the mail.

A U-shaped member 27 is secured to the top 40 of the box 24 and has eyes at the upper ends of its leg portions denoted by numeral 28 to which the ends of the cable are secured as at 29.

A pair of strap members 30—30 extend upwardly from each side of the box 24 and converge over the box and then further extend upwardly as at 31. Each of these portions 31 is equipped with a roller wheel 32 for riding engagement on the horizontal flanges 33 of the inverted T-beam 34. (See Figure 4.)

As shown in Figure 2, each post 7 has a U-shaped framework 35 secured by its end portions to the posts as at 36.

Inside of the frame 35 is the small square 55

frame 37 an upstanding shank 38 of which is secured as at 39 to the upper leg of the frame 35, while the depending shank 40 has the straps *a*—*a* thereof spread apart as at *b* to straddle the up-
5 standing flange of the beam 34 where it is secured as at 42 to the beam, thus suspending the beam in a substantially horizontal position as shown in Figure 1. The mail receptacle 23 is supported on the thus supported track as suggested in
10 Figure 2.

The drive means consists of the box-like structure 44 through the end portions of which the driven shaft 12 is journaled.

Upon the platform 9 is mounted the electric motor 45 the armature shaft 46 of which is connectible with the driven shaft 12 by the clutch generally referred to by numeral 47. This clutch 47 is provided with the collar 48 with which the yoke 49 is engaged, this yoke depending from the slide bar 50 which is slidable through the guides 51—51 on the box 44.

A horizontal rockable arm 52 is pivotally mounted on the post 53 and has a laterally disposed portion 54 at one end to avoid the pulley 11. This lateral portion 54 is provided with the slotted finger 55 through which the cable 19 extends.

The remaining end of the arm 52 is provided with the cam 56 abutting against the plate 57 on the adjacent end of the slide bar 50.

30 Switches 58—59 are provided on the dielectric panel 60 and these have the arms 61—62, respectively, rising therefrom and in the path of the arm 52. These switches 58—59 are for the motor 45 which is reversely wound so that as the enlargement 21 or 22 strikes the portion 55 of the arm 52, for operating one of the switches to start
35

the motor and connect the clutch 47, while in its reverse movement the cam 56 releases the plate 57 to disconnect the clutch and open the motor circuit simultaneously.

Thus the box 23 is stopped automatically at the 5 end of the trackway 24.

It can be seen in Figures 2 and 3 that guide means is provided for the cable, guide rollers 63 for the upper flight of the cable, while an elongated roller 64 is mounted on the lower leg of 10 each frame 35 for guiding the lower flight of the cable 19.

While the foregoing specification sets forth the invention in specific terms, it is to be understood that numerous changes in the shape, size and materials may be resorted to without departing from the spirit and scope of the invention as claimed hereinafter.

Having described the invention what is claimed as new is:—

An article carrier of the character described comprising an endless cable, drive means for said cable, spaced pulleys over which the cable is trained, supporting means for said pulleys, a post, a trackway supported by the post, a receptacle 25 attached to the cable and mounted for longitudinal movement on the trackway, a frame-like structure on the post through which the receptacle is movable, said frame-like structure being provided with a depending portion supporting 30 the trackway, said depending portion provided with a loop-like structure, said loop-like structure serving as a guide for one flight of the cable, and anti-frictional means in the said loop-like structure for said cable. 35

GUY SPENCER.
